LUTHER A. OWENS, OF FELLOWS, CALIFORNIA.

ROTARY DRILL.

1,076,515.

Specification of Letters Patent.

Patented Oct. 21, 1913.

Application filed November 29, 1912. Serial No. 734,100.

To all whom it may concern:

Be it known that I, LUTHER A. OWENS, a citizen of the United States, residing at Fellows, in the county of Kern and State of California, have invented new and useful Improvements in Rotary Drills, of which the following is a specification.

This invention relates to rotary drills, and more particularly to rotary drills for producing deep wells, in which operation a drilling device with suitable bits is actuated to produce the hole by and through the agency of a drill pipe or string which is rotated at the surface through a rotation-imparting mechanism, such as the rotary top commonly employed at the present time. In usual practice the upper end of the drill pipe is connected with the lower end of a swivel stem which in turn is mounted for rotation upon a swivel cross head suspended above the hole by the over-head rig or hoist, and permitting the rotation of the drill pipe or string as above referred to. Breakage frequently occurs at the swivel stem or the point of connection between the same and the drill pipe. The drill pipe and the entire drilling string is then allowed to fall, stopping up the hole and preventing further drilling until the obstruction has been cleared away, which involves great loss of time and money coupled frequently with extensive damage. In order to obviate the possibility of such fracture or breakage under torsion, I provide means acting to sustain and hold up the drill pipe and the whole drilling string upon the failure of the swivel stem or its connection with the drill pipe. This means is normally inactive and does not interfere with or affect the rotation of the drill pipe and string, but immediately acts and becomes effective upon the breakage or failure to act as specified. By the employment of such means, which may be defined as safety means, all of the damage and loss attendant upon breakage or failure of the swivel stem and the consequent dropping of the drilling string is obviated, and the drilling operation may be proceeded with with assurance of absence of any possibility of such loss or damage.

The invention has for its object to provide

improved safety means of the general nature stated, or an improved organization of rotary drill mechanism inclusive of or supplemented by such safety means, which will be superior in point of relative simplicity and inexpensiveness of construction and organization, facility in installation and attachment and detachment and adjustment, positiveness in operation and length of life, and which will be generally superior in efficiency and serviceability.

With the above and other objects in view, the invention consists in the novel and useful provision, formation, construction, combination, association and relative arrangement of parts, members and features, all as hereinafter described, shown in the drawing, and finally pointed out in claims.

In the drawing:—Figure 1 is a fragmentary vertical section of a portion of the drill pipe and swivel stem and swivel cross head of rotary drilling apparatus, to which is shown applied improved safety means organized in accordance with the invention; Fig. 2 is a side elevation of the same taken in a line of vision at right angles to that of Fig. 1; Fig. 3 is a transverse sectional view taken upon the line X³—X³, Fig. 1; and Fig. 4 is a similar view taken upon the line X⁴—X⁴, Fig. 1, and looking in the direction of the appended arrows.

Corresponding parts in all the figures are designated by the same reference characters.

Referring with particularity to the drawing, A designates a portion of the drill pipe, B designates the swivel stem, C designates the swivel cross head, and D designates means whereby the swivel cross head and the drilling string are suspended during rotation of the drilling string relative to the swivel cross head, all depending from the over-head rig or hoist which is controlled from the drum or the like in the usual or any preferred manner. At the upper end of the swivel stem B is detachably applied a collar or the like E between which and the swivel cross head are interposed roller bearings or other anti-friction devices F whereby the weight of the drilling string is rotatively imposed upon the swivel cross head.

G designates a collar by which the swivel

stem C is detachably connected with the drill pipe A; and H designates safety means normally inactive, and acting upon failure of the swivel stem or at the connecting collar G, to support the drill pipe and the entire drilling string by co-action with the collar G. The safety means H are operatively connected with the swivel cross head C by link members h which extend between the swivel cross head and a suspending member k which may be of any preferred and suitable organization, and is shown as comprising a so-called casing elevator the principal use of which is to withdraw well eas-
 5 ing from the well hole, and which, as shown, comprises two semi-circular members 5 and 6 hinged together as at 7 and adapted to loosely surround the drill pipe A in the present service, beneath the collar G, and
 10 slightly spaced therefrom; a suitable securing device 8 being engaged with projecting heads 9 and 10 at the free ends of the members 5 and 6 to hold said members in working position after the pipe has been received
 15 between said members. This suspension member k may thus be readily applied to and detached from the drill pipe at the working position beneath the collar G. The link members h, which are connected with
 20 the respective members 5 and 6 of the suspending member k at diametrically opposed points, each comprise eye-rods 11 and 12 the eyes of the rods 11 being detachably connected with the respective members 5 and 6,
 25 and the eyes of the rods 12 being detachably connected with lugs 13 diametrically oppositely projecting from the swivel cross head C equidistant from diametrically oppositely projecting lugs 15 upon said swivel cross
 30 head and with which the lower ends of the suspension means D are connected. Each pair of eye-rods 11 and 12 is connected together by a turn buckle 16 permitting adjustment to vary the degree of clearance of
 35 the suspending member k from and beneath the collar G.

In the operation of the drilling string, if the swivel stem B fails as by breakage or disconnection at the joint to which is ap-
 40 plied the collar G, the drill rod and entire drilling string falls slightly, dependent upon the space between the collar G and the suspending member k, bringing such collar down upon such member; whereby the en-
 45 tire drilling string is suspended through the collar and the member k together with the link members h and the swivel cross head C by which the load is in turn imposed upon the suspension means D. The drilling string is thus prevented from falling into the hole, and the loss and damage attendant upon such falling, as above pointed out, are obviated.

It is manifest that I may make many variations and alterations in construction

and organization with respect to the disclosure of the foregoing description and the drawing, in adapting the improvements to varying conditions of use and from considerations of preference and general adaptability, all without departing from the spirit of the invention; and I therefore reserve the right to all such alterations, variations and modifications as come within the fair spirit and scope of the invention. 70

Having thus described my invention I claim and desire to secure by Letters Patent: 75

1. The combination, with a rotary drilling string provided with a swivel cross head and means for suspending the entirety in the drilling operation; of means connected with the swivel cross head and acting to sustain the drilling string upon failure of the means of connection between the same and the swivel cross head. 80

2. The combination, with a drilling string provided with a swivel cross head and means for suspending the entirety during the drilling operation; there being a swivel stem whereby the drilling string is rotatively suspended from the swivel cross head, and a collar connecting the drilling string and the swivel stem; of means normally spaced beneath said collar and co-acting with the same and with the swivel cross head to sustain the drilling string upon failure of the swivel stem. 90

3. The combination, with a drilling string provided with a swivel cross head and means for suspending the entirety during the drilling operation; there being a swivel stem whereby the drilling string is rotatively suspended from the swivel cross head, and a collar connecting the drilling string and the swivel stem; of means normally spaced beneath said collar and co-acting with the same and with the swivel cross head to sustain the drilling string upon failure of the swivel stem; said latter means comprising a member surrounding the drilling string beneath the collar, and adjustable means extending between the same and the swivel cross head. 100

4. The combination, with a rotary drilling string and a swivel cross head in connection with which the drilling string is rotatively suspended; said swivel cross head being provided with pairs of spaced lugs; of suspension means connected with one pair of said spaced lugs, and means acting to sustain the drilling string upon failure of the means normally sustaining the same, said means so acting being connected with the other pair of said lugs upon said swivel head. 115

5. The combination, with a rotary drilling string and a swivel cross head from which the drilling string is rotatively suspended; of means connected with the swivel cross head and acting to sustain the drilling string 120 125 130

upon failure of the means normally sustaining the same, and suspension means for the swivel cross head, said means so acting to sustain the drilling string and said suspension means being both connected with

5 said swivel cross head.

In testimony whereof, I have signed my

name to this specification in the presence of two subscribing witnesses.

LUTHER A. OWENS.
